UNITED STATES PATENT OFFICE.

EDWARD B. ALLEN, OF NEWTOWN, CONNECTICUT, ASSIGNOR TO THE SINGER MANUFACTURING COMPANY, OF ELIZABETH, NEW JERSEY, A CORPORATION OF NEW JERSEY.

BUTTONHOLE-SEWING MACHINE.

Application filed December 15, 1923. Serial No. 680,833.

To all whom it may concern:

Be it known that I, EDWARD B. ALLEN, a citizen of the United States, residing at Newtown, in the county of Fairfield and 5 State of Connecticut, have invented certain new and useful Improvements in Button-hole-Sewing Machines, of which the following is a specification, reference being had therein to the accompanying drawings.

10 This invention relates to buttonhole sewing machines and has for an object to provide a machine for sewing a novel four-thread buttonhole, such as that disclosed in my copending application Serial No. 15, 15 680,832, filed herewith. A further object of the invention is to provide a two-needle buttonhole sewing machine having a rotary turret with means for keeping the needle threads from entangling or twisting with 20 one another.

To the ends in view the invention is preferably embodied in a buttonhole sewing machine which, except as hereinafter described, is constructed substantially in 25 accordance with the disclosure of my Patent No. 15,324, reissued April 4, 1922, and the patent to Allen & Faulkner, No. 1,372,473, of March 22, 1921. Such a machine has a travelling work-clamp and a rotary turret 30 for the under thread mechanism; the upper thread mechanism including a needle-bar which is mounted to turn with said turret in sewing around the eye-end of a buttonhole. According to the present invention 35 the needle-bar of my prior machine has been fitted with two closely spaced needles, each carrying an upper thread. The under thread mechanism includes two alternately acting threaded loopers from which loops of under 40 thread are seized by auxiliary loopers or loop-detainers and held in position for entry by the descending needles. Difficulty was experienced in leading the two upper threads to the needles and preventing entanglement and twisting of such threads with one another. This difficulty has been 45 successfully overcome by providing the hollow needle-bar with separate passageways for the respective needle-threads and by disposing the upper entrance to one of the 50 passageways at a level above the entrance to the other passageway.

In the accompanying drawings, Fig. 1

is a side elevation, partly in section, of a 55 buttonhole sewing machine embodying the invention. Fig. 2 is a fragmentary elevation of the rotary turret and stitch-forming instrumentalities of the machine. Fig. 3 is a longitudinal section, in larger scale, of the needle-bar of the machine. Figs. 4 and 60 5 are, respectively, right and left side elevations of the rotary turret and under thread mechanism. Fig. 6 is a plan view 65 of the under-thread mechanism. Fig. 7 is a perspective view of the loop-detaining elements of the under thread mechanism. Fig. 8 is a similar view of the alternately acting threaded loopers with which the loop-detainers of Fig. 7 cooperate and Figs. 9 to 15, inclusive, are perspective views illustrating various stages in a cycle of operations of the stitch-forming instrumentalities. 70

In the preferred embodiment of the invention, as illustrated and described in my 75 said reissued Patent No. 15,324, the frame of the machine is constructed with the hollow rectangular base 1 including the bed-plate 2 from which rises the standard 3 of the bracket-arm 4 terminating in the hollow head 5. The bed 2 supports the usual 80 travelling work-clamp 6 to which longitudinal feeding and sidewise shifting movements are imparted by the usual connections with the feed-wheel 7 for spacing the over-seaming stitches of a buttonhole. The main-shaft 8 is journaled within and longitudinally of the base 1 and is geared by the usual 1 to 2 speed-multiplying connection to the upper or needle-operating shaft 9. 85

In general construction and arrangement 90 of parts the needle-actuating mechanism of the present machine is substantially the same as that disclosed in said Allen & Faulkner patent; the tubular needle-bar 10 being journaled as usual for reciprocating and turning movements in the head 5 and at its lower end carrying the yoke 11 and cross-pin 12 on which slides the jogging needle-block 13 carrying two closely spaced needles 13' which descend simultaneously 95 through the aperture 14, Fig. 8, in the needle-throat 15 carried by the rotary turret 16.

The lower thread mechanism is carried 100 by the rotary turret 16, the tubular shank 17 of which is journaled as usual in a verti-

cal bearing in the frame block 18. Extending upwardly from the turret 16 is a post 19 into the upper end of which is threaded a horizontal screw-pin 20 upon which is 5 journaled a looper-carrier 21 formed with oppositely extending arms to which are rigidly secured the right and left-hand threaded loopers 22, 23. The looper-carrier 21 is given rocking movements by means 10 of the link connection 24 with the usual vertically reciprocating sleeve 25 telescopically received within the turret shank 17 and driven by suitable mechanism such as disclosed in said Allen & Faulkner patent.

15 Cooperating with the threaded loopers are the alternately acting loop-detainers 26, 27, which are fulcrumed on the cross-pin 28 carried by the posts 29 on the turret 16. The loop-detainers are moved simultaneously in 20 opposite directions by the usual link connections 30 to the cross-head 31 carried by the vertically reciprocating rod 32 extending downwardly within the sleeve 25. The loop-detainer mechanism is substantially the same 25 as that disclosed in said Allen & Faulkner patent. In the present machine, however, the detainers 26, 27, each operate to seize a loop of under or looper thread from its respective looper 22, 23 and hold such loop in 30 position for entry by the needles 13.

To overcome twisting and excessive friction on the needle-threads, the tubular needle-bar 10 is formed with separate passageways constituted preferably by the 35 thread-tubes 33, 34 fitted within the needle-bar 10. As will be observed, one of the thread-tubes 34 extends above the upper end of the other thread-tube 33 and this provision assists materially in keeping the 40 needle-threads effectively separated as the needle-bar turns in sewing around the eye-end of the buttonhole and in resuming initial position after the sewing is completed. The needle-threads are preferably led 45 through separate tension devices 35, 36 and separate apertures in the post 37; thence under the auxiliary take-up bar 38 and down through the thread-tubes 33, 34 to the respective needles 13. The auxiliary take-up 50 38 is preferably constructed substantially in accordance with the disclosure of my Patent No. 1,482,671, dated February 5, 1924; the top ends of the thread-tubes 33, 34, in the present machine, dipping below the level of 55 the cross-bar 38 at the end of the downstroke of the needle-bar, thereby overcoming a tendency of the needle-threads to twist between the needle-bar and the post 37.

In the operation of the machine, Fig. 9, 60 the needles 13 pass their respective loops through a loop 44 of an under thread held spread by the detainer 27. The detainer withdraws and as the needles rise, Fig. 8, 65 their loops 39, 40 are seized by the looper 23 which projects a loop 41 of a second under

thread, Fig. 11, through the upper thread loops 39, 40.

The loop-detainer 26 advances and seizes the loop 41 of under thread after which the looper 23 withdraws, leaving its loop 41 on 70 the detainer 26, Fig. 12, which detainer holds the loop 41 in position for entry by the needles 13 on their next descent, Fig. 13.

As soon as the loop 41 is entered by the needles, the detainer 26 is withdrawn to 75 shed such loop. As the needles rise, Fig. 14, they throw out loops 42, 43, which are seized by the looper 22 carrying an under thread, a loop 44 of which thread is thereby passed through the upper thread loops 42, 80 43, Fig. 15. The loop 44 is next seized by the detainer 27 and presented to the needles, 13, as shown in Fig. 9. This completes a cycle of operations.

Having thus set forth the nature of the 85 invention, what I claim herein is:—

1. Overseaming stitch-forming mechanism for sewing machines comprising, in combination, upper-thread mechanism having a plurality of jogging needles fixed relatively 90 to one another, and under-thread mechanism comprising a pair of threaded loopers each of which seizes thread-loops from both of said needles.

2. Overseaming stitch-forming mechanism 95 for sewing machines comprising, in combination, upper-thread mechanism having a plurality of needles fixed relatively to one another, and under-thread mechanism comprising a pair of threaded loopers each of 100 which seizes thread-loops from both of said needles and a pair of loop-detainers cooperating with said threaded loopers and needles.

3. Overseaming stitch-forming mechanism 105 for sewing machines comprising, in combination, upper-thread mechanism having a plurality of jogging needles fixed relatively 110 to one another, and under-thread mechanism including a pair of oppositely directed and threaded loopers cooperating alternately with said needles.

4. Overseaming stitch-forming mechanism for sewing machines comprising, in combination, upper-thread mechanism having a 115 plurality of jogging needles fixed relatively to one another, and under-thread mechanism including a pair of oppositely directed and threaded loopers cooperating alternately with said needles and a pair of loop-detainers 120 acting alternately to seize loops of under-thread from the respective loopers and present such loops for entry by said needles.

5. A multiple-needle sewing machine having a hollow reciprocating and axially turning needle-bar provided with separate passageways for the respective needle-threads, 125 said passageways having their entrances disposed at different elevations.

6. A multiple-needle buttonhole sewing 130

machine having a hollow reciprocating and axially turning needle-bar provided with separate passageways for the respective needle-threads, said passageways having their entrances disposed at different elevations, a thread-guiding post having separate thread-eyes, and an auxiliary take-up bar adjacent said needle-bar, the upper ends of said passageways dipping below the level of said auxiliary take-up bar at the end of the 10 downstroke of the needle-bar.

In testimony whereof, I have signed my name to this specification.

EDWARD B. ALLEN.
